UNITED STATES PATENT OFFICE.

CARRODUS BASTOW, OF ALLWOOD, NEW JERSEY, ASSIGNOR TO AMERICAN WHOLE-SALE CORPORATION, OF BALTIMORE, MARYLAND, A CORPORATION.

DESIGN FOR AN OILCLOTH TABLE-COVER.

60,082.

Specification for Design.

Patented Dec. 27, 1921.

Application filed August 25, 1921. Serial No. 495,410. Term of patent 7 years.

To all whom it may concern:

Be it known that I, CARRODUS BASTOW, a citizen of the United States, and a resident of Allwood, in the county of Passaic and State of New Jersey, United States of America, have invented a new, original, and ornamental Design for an Oilcloth Table-Cover, of which the following is a specification.

Reference is to be had to the accompanying drawing, in which the figure represents a top view of a table cover embodying my new design.

I claim:

The ornamental design for an oilcloth table cover, as shown.

CARRODUS BASTOW.
